UNITED STATES PATENT OFFICE.

LEAHMAN S. MOSES, OF NEW YORK, N. Y., ASSIGNOR TO CLARENCE S. MAYER, OF NEW YORK, N. Y.

GARMENT-HOLDER.

1,054,861.

Specification of Letters Patent.

Patented Mar. 4, 1913.

Application filed December 16, 1911. Serial No. 866,125.

To all whom it may concern:

Be it known that I, LEAHMAN S. MOSES, a citizen of the United States, and a resident of the city, county, and State of New York, have invented certain new and useful Improvements in Garment-Holders, of which the following is a specification.

My invention relates to a novel garment clasp or holder and the object thereof is to provide a very simple holder to be secured to the waist band of men's trousers for the purpose of engaging the outer shirt, for the purpose of keeping it down in the front to prevent wrinkling up during the twisting and bending of the wearer.

My object is to produce a device of this character which will be simple and inexpensive to make and which can not only be very easily attached to and detached from the shirt, but one which will securely hold the shirt without cutting or wearing the shirt where it is attached to it.

The holder is preferably permanently attached to the trousers, as by sewing it there-to, and is temporarily or detachably secured to the shirt so as to be readily disengaged from the latter.

The novel construction of my improved device will be fully set forth hereinafter. In the drawing forming a part of this application, Figure 1, is a front elevation showing the trousers and shirt, and my invention located at the most advantageous position, Fig. 2, is a perspective view showing my device attached to the interior of the trousers waist band, Fig. 3, is a front elevation of the device attached to the trousers waist band, Fig. 4, is a section view taken on the line 4-4 of Fig. 3, Fig. 5, is a plan view thereof, Fig. 6, is a rear elevation thereof, Fig. 7, is a perspective view showing the manner of attaching the device to the shirt, and Fig. 8 is a section view taken on the line 8-8 of Fig. 6.

The present device is preferably secured to the trousers waist band, inside, and near the middle of the front of the trousers. I have shown a base plate 1, having apertures 2, at the several corners thereof, and this plate is shown secured to the trousers waist band 3, by stitches 4, which engage through the apertures 2. The plate 1, is preferably flat and of metal and from the same metal there are found raised projections 5, which are stamped up from the plate metal 1.

The latter is cut at the lines 6, and 7, so that the projections 5, may be raised above the plane of the base and the latter are arranged horizontally on the plate, and are of convex shape, as is clearly shown in Fig. 6. The several projections 5, are separately arranged, that is, they are connected at each end with the base plate and spaced by the plate at 5°, so that they have little or no resiliency with reference to the base plate. As the projections 5, are separated along the lines 6 and 7, from the base, and extend outwardly, they have free upper and lower edges 8, and 9,

Preferably integral with the base I have formed a resilient member 10, which curves out from one end of the base at the point 11, and runs horizontally, and substantially parallel with the latter, preferably beyond the end of the base; and is curved outwardly slightly at its free end 12, to facilitate the slipping of the shirt hem in between the tongue 10 and the base. The tongue 10 is free at one end and is therefore more or less resilient, so that it may be separated from the base as may be required, and it has a tendency to resume the position shown in Fig. 4. This tongue has a longitudinal opening 13, of sufficient width to allow it to straddle the projections 5, and the edges 14, of the opening 13, are adapted to lie close to the upper and lower edges 8, and 9, of the projections with which they co-operate in holding the shirt material.

The holder as above set forth, is secured to the inside of the trousers, and after the shirt is tucked in the top of the trousers, with the front placket 15, coming down about in line with the holder, the outer edge 16, of the shirt is slipped in between the tongue 10 and base 1, and is moved along between the projections 5, and tongue until the edge 16, passes over the last projection. Since the projections 5, are curved and extend horizontally; and since the tongue 10 is resilient the shirt material may be thus inserted very easily, and without straining or wearing it. When thus placed, the shirt material will be slightly curved over the tops of the projections 5, and will be firmly held from sliding upwardly, which is the direction of the strain between the shirt and trousers, by gripping action of the edges 8 and 9, of the projections, and the co-operating edges 14, of the tongue. The shirt ma-

terial is held by a sort of bighting action in the one direction (upwardly) but is readily moved horizontally relatively to the holder.

To disengage the shirt the edge thereof is 5 simply withdrawn sidewise from the holder.

I have found that a holder constructed as above may be very easily and cheaply stamped from sheet metal and when used it 10 firmly holds the shirt down, but the shirt 15 may be very easily engaged with or disengaged from the holder.

A holder of the above character is unobserved, and unobstructive, but it holds the shirt down, keeping it smooth and neat in 15 appearance.

Having described my invention what I claim is:—

A garment holder, comprising a base

plate, curved projections extending outwardly therefrom and having edges separated from the base plate along their projecting sides, said projections being connected with the base plate at each end, and a movable tongue having an opening defined by substantially straight horizontal edges 25 and adapted to straddle said projections, the edges of said tongue and said projections being arranged to coöperate in holding the garment material in a direction laterally of said projections. 30

Signed at the city, county and State of New York, this 14th day of December 1911.

LEAHMAN S. MOSES.
